UNITED STATES PATENT OFFICE

1,921,592

PAWL CONVEYER FOR CONTINUOUS HEATING FURNACES

Randal E. Talley, Irwin, Pa., assignor to George J. Hagan Company, Pittsburgh, Pa., a Corporation of Pennsylvania

Application May 15, 1931. Serial No. 537,562

4 Claims. (Cl. 263—6)

This invention relates to heating furnaces, particularly to improvements in conveying mechanism for continuous heating furnaces and it is among the objects thereof to provide conveying apparatus which shall be especially applicable for the conveying of bars, sheets, rounds, annular blanks and the like which are of such shape that they cannot readily be pushed through the furnace, one against the other.

10 The invention briefly consists of a movable hearth member disposed longitudinally of a furnace comprising one or more reciprocating members provided with self-aligning work-engaging pawls which are normally disposed to engage the work in one direction of movement of the reciprocating member and adapted to pass underneath the work in the return movement of the reciprocating member.

15 The invention further provides for coordination of the door operating and conveyer reciprocating mechanisms.

20 These and other objects will become more apparent from a consideration of the accompanying drawings forming a part hereof, in which like reference characters designate like parts and in which Figure 1 is a longitudinal-vertical section of a furnace showing conveyer mechanism embodying the principles of this invention; Figure 2 a cross sectional view of the conveyer mechanism taken along the lines II—II, of Fig. 1; and Fig. 3 a wiring diagram of the electrical connections which diagrammatically illustrates the motor, the motor control, and motor starting elements for coordinating the movements of 25 the conveyer and door operating mechanisms.

25 With reference to Figures 1 and 2 of the drawings, the structure therein illustrated comprises an enclosing wall structure consisting of end walls 1 and 2, side walls 3, and a roof 4 which 30 together with the hearth, form a heating furnace in which the conveyer mechanism generally designated at 5 is disposed.

35 Below the hearth of the furnace is an arrangement of fire box and flues the details of 40 which are not essential to the description of the present invention.

45 End walls 1 and 2 of the furnace are provided with doors 6 and 7, the door 6 being suspended from pulleys 8 and provided with a balancing counterweight 9, and the door 7 being 50 similarly mounted but adapted to be motor operated through a chain 10 and operating crank 11, gear reduction unit 12, a door motor 13 and a limit switch generally designated at 14.

55 The conveyer mechanism 5 consists of a pair

of reciprocating rails 15 disposed in longitudinal guides and work supports 16, Figure 2, the reciprocating rail being connected by cross bars 17 and operated through a link 18 pivoted at 19 to a floor bracket 20. The link is loosely connected to the rails 15 by a slotted opening 21 60 engaging the cross bar 17 shown in Figure 2. Mounted on the reciprocating rails are a plurality of pawls 23 having weighted ends 24 which normally rest against the bottom of the 65 rails and hold them with their work-engaging faces 25 perpendicular to the line of travel of the reciprocating rails.

The engaging pawls are mounted in longitudinal spaced relation, as shown in Figure 1, 70 their spacing corresponding to the spacing of the work which in the illustration consists of flat bars 26 which bars are manually or automatically pushed from the receiving platform 27 onto the guide members 16, the bars being 75 illustrated as extending across and supported on the guides 16 in Figure 2 of the drawings.

The reciprocating rails are actuated by a connecting rod 28 joined to link 18 at 29 and mounted on a crank 30 which is rotated through 80 a gear drive 31 by a conveyer motor 32.

The operation of the conveyer motor is controlled by a limit switch 33 in a manner to be explained in connection with Figure 3 of the drawings.

85 As shown in Figure 3, a time clock diagrammatically illustrated and generally designated at 34 is electrically connected to a power line. The clock is driven by a synchronous motor 35 which through a cam 36 operates the movable contact 37 that engages with a stationary contact 38 to close the circuit of a control relay 39. The control relay through contacts 40 and 41 controls the motor starters 42 and 43 which energize the door operating motor 13 90 and the conveyer motor 32.

95 The operation of the conveyer mechanism and the door operating mechanism is briefly as follows: The time clock is set to periodically close contacts 37—38 at timed intervals, thereby energizing motors 13—32 simultaneously. The conveyer motor, when energized drives the crank 30, which in turn actuates the link 18 causing the rails 15 to be reciprocated. As previously explained the pawls 23 engage the work 105 when the rails 15 are travelling in the direction from the front towards the rear of the furnace and on the return movement of the rails the pawls slide under the bars 26 and when the top of the pawl has cleared the bars, 110

they are again automatically replaced to their normal position with their weighted portions 24 resting on the bottom of the rails. By this reciprocating motion the bars are advanced 5 step-by-step through the furnace until they reach the discharge opening through which they are discharged into a quenching tank or upon a suitable transporting device.

When the conveyer motor is energized, gear 10 31 is rotated counter-clockwise causing the pin 44 to pass out of engagement with the operating finger of limit switch 33 thus allowing the switch to close.

After a brief interval of time, contact 40 of 15 the control relay opens, due to the opening of the contacts 37-38 of the time clock, but current is still maintained in the coil of the motor starter 42 because limit switch 33 is closed. When the gear 31 has made one complete revolution 20 its projecting pin 44 will again engage the lever of the limit switch 33 and open the contacts of this switch. This interrupts the current in the coil of the motor starter 42, the contacts of the motor starter open and the conveyer motor stops. Simultaneously with the starting of the conveyer motor by the closing of the contacts 40 the motor for opening the discharge door 7 is also started by the closing 25 of the contacts 41. The door operating mechanism functions in the identical manner as the conveyer mechanism described above. Both motors are started at the same time by the closing of the control relay 39 and are stopped independently by the engagement of projecting pins 44 and 45 with the respective limit 30 switches 33 and 14 when the operating cycle of each is completed.

It is of course possible to operate the charging door 6 in the same manner as the door 7 to synchronize with the movement of the conveyer mechanism, and it is also evident that other means may be employed for synchronizing the operation of the door with the movement of the conveyer mechanism so that the door is closed excepting for the brief intervals during which the work is being discharged from 45 the furnace chamber.

It is evident from the foregoing description of this invention that the conveyer mechanism constructed in accordance therewith provides simple and efficient means for conveying articles such as bars, plates, sheets, and articles of irregular form which cannot be conveyed through a furnace by ordinary pusher types of charging mechanism, but which must be individually engaged by some conveying means to prevent their buckling and piling up on the furnace hearth.

Although one embodiment of the invention has been herein illustrated and described it will be obvious to those skilled in the art that various modifications may be made in the details of 60

construction without departing from the principles herein set forth.

I claim:

1. In a continuous heating furnace the combination with a pair of stationary guides constituting work supports on which the work is adapted to rest, a plurality of reciprocating rails in said guides and below the work supporting surface thereof, work engaging pawls pivotally mounted on said reciprocating rails and adapted to project above the work supporting surface of 80 said guides, and means for subjecting the reciprocating members to movement in one direction whereby the pawls engage the work and advance it through the furnace and for returning said reciprocating member to its original position whereby the pawls are depressed to pass below the work and the work remains stationary 85 on its supports.

2. In a continuous heating furnace having a charging opening and a discharge opening, a door for said last named opening, automatic means for opening and closing said door, a work support in said furnace, reciprocating means extending longitudinally of and beneath the upper edge of said work support, a plurality of work engaging pawls pivotally mounted on said reciprocating means, automatic means for actuating said reciprocating means at predetermined timed intervals, means for actuating said 100 door operating means and a common control for said reciprocating and door operating means whereby the latter is actuated in response to the movements of said reciprocating member.

3. In a continuous heating furnace a motor driven reciprocating conveying mechanism adapted to advance the articles to be heated step-by-step from the charging to the discharge end of the furnace, a motor driven door operating mechanism, a common control for energizing the 110 starter coils of said motors, a time clock for rendering said control operative at predetermined intervals, and limit switches actuated by their respective motors to interrupt the circuits of 115 said motors.

4. In a continuous heating furnace a pair of guide rails constituting work supports extending longitudinally of said furnace, reciprocating bars disposed in said guide rails and adapted for sliding movement therein, work engaging pawls pivotally mounted on said bars in transverse alignment and longitudinal spaced relation, means for actuating said bars in one direction 125 whereby said pawls engage the articles supported by said guide rails and advance them toward the discharge end of the furnace, and means for actuating said bars in the opposite direction whereby the pawls are released from their engagement with the work and returned to their 130 initial position.

RANDAL E. TALLEY.
